UNITED STATES PATENT OFFICE

2,532,465

METHOD FOR SPINNING ARTIFICIAL FILAMENTS

Richard W. Stanley, Lakewood, Ohio, assignor to American Viscose Corporation, Wilmington, Del., a corporation of Delaware

Original application April 22, 1944, Serial No. 532,328. Divided and this application November 3, 1949, Serial No. 125,188

5 Claims. (Cl. 18—54)

1

This invention relates to improved methods for continuously spinning artificial filaments or threads. This application is a division of my copending application Serial No. 532,328, filed April 22, 1944, now Patent No. 2,516,157.

It is an object of the invention to provide an improved method for continuously spinning, manipulating, and treating artificial threads in which the section carrying the coagulating liquids which are generally the most corrosive is so arranged with respect to the liquid after-treating section in which less corrosive liquids are used that there is little opportunity for spray from the coagulating bath and the thread handling devices associated with the coagulating bath to be carried over to the thread as it is discharged from the after-treating liquid section. Arranged intermediate the coagulating bath and the after-treatment section, there is provided in accordance with the objects of this invention, a stretching zone which forms a component part of what is hereinafter termed the forming section and in which the thread may be treated with any suitable plasticizing liquid, which in the case of viscose may be hot water or hot dilute acid. These two distinct sections are so arranged that the discharge end of the liquid after-treatment section is at the part thereof farthest from the forming section and is beyond the reach of operators employed along the coagulating bath and conversely the forming section of the machine is out of reach of operators employed along the after-treatment section.

A further object is to so arrange the sections of the process that the entire spinning or treating unit of each single end thread-producing station will be readily and conveniently accessible to the operators assigned to the respective working faces of the machine adapted to carry out the process. A further object is to provide a spinning process having a compact liquid after-treatment section in which all of the after-treating liquids (excluding the stretching bath which is herein considered to constitute a forming liquid as distinguished from an after-treating liquid) are applied to a single continuous helix of the thread. The present invention also provides for drying and/or collecting the after-treated yarn in a section provided at a different floor level than that of the coagulating and after-treating sections.

Other objects and advantages of the invention will appear from the description hereinafter in which reference to the drawing will be made.

Figure 1 is an end elevation, partially in cross-

2

section, of a machine adapted to carry out the process of the invention.

Figure 1a shows in elevation an alternate way of collecting the filaments,

5 Figure 2 is a plan view,

Figure 3 is a side elevation showing the coagulating bath working face,

Figure 4 is a plan view, partially in cross-section, showing the coagulating bath and associated parts in more detail.

The spinning machine shown for carrying out the process of the invention has the coagulating bath working face 2, the after-treatment section 3, which are both on the same floor level, and 15 the drying and/or collecting section 4 on a lower floor level or deck. The forming section comprises a deep, narrow trough 5 for the coagulating bath extending the length of the machine and the spinnerets 6 are arranged to spin generally vertically upwardly to the thread-advancing devices 7 disposed above the rear portion of the bath. As shown, these devices comprise two godets, the upper and larger of which is driven and the other is an idler. Alternatively, a 20 thread-advancing reel or a pair of driven godets of the same size may be used. A guide 8 serves to control the thread as it proceeds to the thread-advancing device 7 and also to remove excess coagulating liquid from the thread.

25 A hollow framework in the form of an intermediate longitudinal pedestal 9 supports a housing 10 for the mechanism 11 for driving the thread-handling devices including the devices 7 and the thread-advancing devices 12 in the liquid after-treatment section of the machine. The housing 10 is provided with a jacket 13 of corrosion resistant material, such as lead spaced from the walls of the housing and having openings 14 about the shafts, both drive and idler, 30 for the thread-handling devices 7 and 12. An inert or non-injurious gas, such as air, preferably dry, is forced into the space between the jacket and the main housing walls from a suitable duct 10a (see Fig. 2) or ducts at one or both ends of the machine. The hollow pedestal constitutes a duct through which the foul air in the vicinity of the coagulating bath is removed, suitable openings 15 being provided in the pedestal all along the machine adjacent the top of the trough 5, and one or two suitable exhaust ducts being provided, such as at one or both ends of the machine, and being connected to exhaust fans. Similarly a duct 16 extending the length of the machine is provided in the upper region of 35 the hood 17 comprising suitable sash means 17a

by which the spinning stations of the machine are readily accessible to the operators. The duct 16 is provided with openings 18 (preferably adjustable in any conventional manner) in the base thereof facing the receptacle or receptacles 19 for the plasticizing liquid. The provision of the upper exhaust duct 16 and that in the pedestal 9 assures that the foul air will be drawn away from the operators while they are manipulating the thread in lacing up the machine or tending to it at any other time. In addition, the provision of an inert gaseous medium under elevated pressure within the jacket 13 about the housing for the driving mechanism protects this mechanism from any foul, corrosive atmosphere that may hover about the coagulating section of the machine.

The driving godets of the devices 7 are set at an acute angle to the longitudinal axis of the machine so that they are off-set laterally and axially from each other in staggered relationship. The reels 12 are similarly staggered so that the threads proceed at an acute angle from the upper godets through their respective troughs 19 to their respective after-treating reels 12. By this arrangement, it is possible to obtain a long immersion through the stretch baths in troughs 19 without having the receiving ends of the reels 12 beyond the reach of operators having average arm length. Preferably, the troughs 19 are placed from three to five feet from the floor level. The troughs 19 may be supplied with liquid, such as hot water or hot dilute acid, by the downwardly extending branches 26 of the feed pipe 24 and adjacent each end with the slotted partitions 22 forming overflow chambers at each end of the trough which discharge in drains 23.

The reels 12 may be provided with a surrounding deflector or guard 24 for controlling the action of the liquids upon the threads and substantially confining the several different liquids applied to their respective treating zones along the helix. This deflector or guard may be of the same construction as that shown in either of the copending applications of Stanley and Lowe, Serial No. 504,664, filed October 2, 1943; and Serial No. 523,402, filed February 22, 1944. Headers 25 having branches 26 conduct the several treating liquids to corresponding treating zones of the helix formed on the reels 12. Discharge pipes 27 connected to the extreme limits of each treating zone lead to troughs 28 which extend the length of the machine for receiving the discharge from the corresponding zones of all the reels 12. The discharge from each of these troughs may be recirculated to the appropriate header, with or without first subjecting it to recovery, replenishment, or purification processes. The troughs 28 or any selected one or more thereof may be replaced with headers connected to pipes 27 in which case the removal of liquid from the respective treating zones may be assisted by suitable suction pumps inserted in the respective headers, especially for operating in accordance with the above-mentioned application Serial No. 523,402.

An inwardly and downwardly sloping trough 29 may be disposed beneath the several troughs 28 and preferably extends to a point beyond the discharge ends of the reels 12. A trough 30 sloping toward one end, or from the middle toward both ends, of the machine serves to discharge any drainings from the trough 29.

The reels 12 are preferably removably supported at both ends, being coupled for driving at their

inner ends and rotatably to a series of posts 31 which are capable of being swung outwardly on their pivots 32 for removing the reels and of being locked in reel-supporting position by the latches 33. Reels 12 are preferably driven at higher peripheral speed than the devices 7 so that a predetermined amount of stretching occurs as the threads pass through the troughs 19.

The threads proceed substantially vertically downwardly from the discharge ends of the reels 12 either to centrifugal collecting buckets 34 through the traversing funnel guides 35 as shown in Figure 1a (where alternate threads are directed by godets 36 and 37 to the opposite row of buckets) or they proceed (as illustrated in Fig. 1) to any suitable form of drying means such as the heated casing 38 in which the respective thread is advanced in the form of a helix about two canted drums 39 and 40, at least one of which is driven, and then to a collecting device, such as the winding machine 41. If desired, the winding machine may be replaced by a cap-twisting or ring-twisting device.

As shown in the drawing, the path for coagulating the filaments or threads is preferably narrow and this is necessary in order that an operator standing at the coagulating bath working face of the machine can readily reach over the bath to pass the threads through the stretching troughs 19 and place them on the receiving ends of the reels 12. As shown in Figures 3 and 4, the connections to supply the spinnerets 6 with spinning material extend through apertures 42 in the outside wall 43 of the trough 5 for the coagulating bath. A bearing 44 of suitable material, preferably resistant to corrosion by the coagulating material is secured in the aperture, such as by welding, so that its axis is inclined in a horizontal plane at a small acute angle, preferably less than 25°, to the normal to the length of the machine. The "rounder" 45 preferably is made of a corrosion-resistant material, such as stainless steel tubing or piping, and has an approximately right angle bend at 46 spaced a short distance from the wall 43 of the coagulating bath trough. The portion of the rounder extending through the wall 43 is provided with a shoulder 47 and is clamped within a sleeve 48 (which is rotatable within the bearing 44) by the nut 49 engaging a threaded portion of the rounder. A handwheel 50 positioned outside the trough 5 is fixed upon the sleeve so that it can be used to rotate the rounder and thus swing the spinneret into and out of the trough. A washer 51 of resilient material, such as soft rubber or synthetic rubber, is provided so that it is forced by hydraulic pressure against a suitable seat or face 52 formed on the bearing 44, thereby sealing the joint against leakage. A hollow region 53 may be formed in the bearing member 44 and may be provided with a suitable drainage connection 53a (Figure 1). The sleeve 48 may be provided with grooves 54 to prevent any liquid leaking from the bath from proceeding beyond the region 53 provided with suitable drainage. An L connection 55 connects the tube 56 which receives the spinning material from the pump 57 to the rounder, a "ball and socket" joint being provided at 58 to permit rotation of the rounder 45 relative to the L 55. A spring pressed pin 59 mounted in the bracket 60 maintains the L 55 firmly in engagement with the rounded end of rounder 45.

The rounder 45 has a long straight portion extending from the bend 46 which merges at 45a with a portion which curves back so that the

spinneret 6 at the end of the rounder directs the filaments or thread produced thereby in an upward direction. This curved portion is bent at 45° so that it lies in a plane approximately parallel to the wall 43 of the trough when disposed in spinning position. It will be seen from Figure 2 that when the rounder is swung into inoperative position, the spinneret is directed downwardly over the waste or draining trough 51 which may be provided with removable waste trays 62. Preferably, the width of the inner web 63 of the bracket 60 is so correlated with the disposition of the spokes 64 of the handwheel 53 that the upper and lower edges of the web 63 serve as detents to limit the rotation of the handwheel to dispose the spinneret in operating position and in inoperative position over the waste trough 51. It will be seen from Figure 4 that the rounders are so constructed and arranged as to permit immersion of the spinneret to a great depth, swinging the spinneret to a point near the bath surface for lacing up the machine and swinging the spinneret to a point over the waste trough, without interfering with each other and the walls of the trough in spite of its narrowness and depth. In Figure 2, the dotted line a—b shows the extreme limit of movement of the rounder away from the wall 43 of trough 5.

In starting the spinning operation, the operator turns the handwheel 53 until the spinneret is at or near the surface of the coagulating bath, threads up the thread-handling device 7 and as the thread is taken up thereby he lowers the spinneret to the bottom of the trough 5, and then takes the thread from the device 7 through one of the stretch baths to the corresponding reel 12. An operator on the other working face of the machine takes the thread as it is discharged from the reel 12 and drops it to the floor below where another operator receives it and laces up whatever collecting and/or drying devices are there. There is no necessity for the operators to carefully synchronize their activities in that each section of the machine can continue to function while waiting for the operator in the next section in advance to send the thread on its way to the next section.

A screen 66 and a plate 67 separate the bath trough 5 from the draining trough 51. The plate is adjustably mounted so that the depth of the coagulating bath may be controlled readily.

It is to be understood that changes and variations may be made without departing from the spirit and scope of the invention as defined by the following claims.

I claim:

1. A method of producing artificial thread comprising the steps of spinning the thread generally vertically upwardly through a coagulating medium, passing the thread through a generally helical path outside the medium while permitting further coagulation by medium carried thereby, then passing the thread approximately horizontally through a plasticizing medium, stretching the thread during its horizontal travel, then passing the thread through a single continuous helical path, and subjecting the thread in succeeding zones of the helix to each of a plurality of treating liquids.

2. A method of producing artificial thread comprising the steps of spinning the thread generally vertically upwardly through a coagulating medium, passing the thread through a generally helical path outside the medium while permitting further coagulation by medium carried thereby, then passing the thread approximately horizontally through a plasticizing medium, stretching the thread during its horizontal travel, then passing the thread through a single continuous helical path, subjecting the thread in succeeding zones of the helix to each of a plurality of treating liquids, completing all liquid treatments as the thread passes through the continuous helical path, and collecting the thread.

3. A method of producing artificial thread comprising the steps of spinning the thread generally vertically upwardly through a coagulating medium, passing the thread through a generally helical path outside the medium while permitting further coagulation by medium carried thereby, then passing the thread approximately horizontally through a plasticizing medium, stretching the thread during its horizontal travel, then passing the thread through a single continuous helical path, completing all liquid treatments as the thread passes through the continuous helical path, passing the thread through a third helical path, drying it as it passes therethrough, and collecting the thread.

4. A method of producing artificial thread comprising the steps of spinning the thread generally vertically upwardly through a coagulating medium, passing the thread through a generally helical path outside the medium while permitting further coagulation by medium carried thereby, then passing the thread approximately horizontally through a plasticizing medium, stretching the thread during its horizontal travel, then passing the thread through a single continuous helical path disposed at about the same level as the first helical path, subjecting the thread in succeeding zones of the helix to each of a plurality of treating liquids, completing all liquid treatments as the thread passes through the continuous helical path, and collecting the thread.

5. A method of producing artificial thread comprising the steps of spinning the thread generally vertically upwardly through a coagulating medium, passing the thread through a generally helical path outside the medium while permitting further coagulation by medium carried thereby, then passing the thread approximately horizontally through a plasticizing medium, stretching the thread during its horizontal travel, then passing the thread through a single continuous helical path disposed at about the same level as the first helical path, subjecting the thread in succeeding zones of the helix to each of a plurality of treating liquids, completing all liquid treatments as the thread passes through the continuous helical path, and collecting the thread at a lower level substantially directly below the discharge end of the continuous helical path.
